ABSTRACT

An air inlet assembly for directing air into an ion chamber of a combustion products detector of the ionization chamber type comprises a shallow flat bottomed cup opening toward an open ion chamber and acts as a closure for completing the chamber; the cup has in its side wall radial slots for directing air flowing in from any side toward the center axis of the cup, a hole in the cup bottom at the central axis utilizes the velocity effect of the air crossing the inside of the cup to draw air in transversely and direct air into the ion chamber. A conducting screen on the cup adjacent the slots restricts somewhat the air flow somewhat and acts as an ion collector. The ion chamber is a right circular cylinder and has a conducting plate on its bottom wall and a radioactive alpha emitter source at the center of the plate; an electric potential is applied to produce a field extending between the plate and the screen and distributed over the chamber cross section.

COMBUSTION PRODUCTS DETECTOR ASSEMBLY AND METHOD OF OPERATION

This invention relates to the detection of products of combustion in the atmosphere and particularly to an improved method and apparatus for effectively sampling the air in a room or other enclosure.

Many smoke or combustion product detectors have been provided heretofore which employ ionization chambers through or over which the ambient air is circulated for sampling and operation of an indicating device or alarm upon the occurrence of a predetermined concentration of combustion product in the air. These devices have proved useful for many applications, however, it has proved difficult to obtain uniform and reliable operation in other installations of the detectors. It is desirable to provide greater reliability and accuracy in the operation of combustion product detectors and accordingly it is an object of the present invention to provide a combustion product detector including an improved arrangement for effecting reliable sampling of the ambient air through a wide range of air flow directions and rates of movement.

It is another object of this invention to provide an improved combustion product detector of the type employing an ion chamber for sensing the presence of combustion product in the ambient air.

It is another object of this invention to provide an improved air inlet assembly for combustion product detectors of the ionization chamber type.

It is a further object of this invention to provide an improved ionization chamber arrangement for combustion product detectors.

Briefly, in carrying out the objects of this invention in one embodiment thereof, an ionization chamber assembly is provided which comprises a right circular cylindrical chamber formed of insulating rigid synthetic plastic and an air intake assembly arranged to admit air and direct it radially toward the central axis of the chamber. Air is further caused to flow axially of the chamber and direct a portion of the air toward the cylindrical chamber which contains a radioactive element for emitting alpha particles for ionization of air. A metal screen in the intake assembly restricts the maximum rate of flow of air into the chamber and also acts as the ion collecting plate of the device. The dimensions of the ion chamber are proportioned to optimize the sensitivity of the detector.

The features of novelty which characterize this invention are pointed out with particularity in the claims annexed to and forming a part of this specification. The invention itself, however, both as to its organization and its method of operation, together with further objects and advantages thereof, will best be understood by reference to the following description taken in connection with the accompanying drawings in which:

FIG. 1 is a somewhat diagrammatic elevation view partially broken away of a device embodying the invention;

FIG. 2 is a side elevation view of the ionization chamber assembly of the device;

FIG. 3 is a sectional view of the device as shown in FIG. 2; and

FIG. 4 is a top plan view of the device partially broken away.

Referring now to the drawings, the combustion products detector shown in FIG. 1 has been illustrated in its position for ceiling mounting. The detector is of the

ionization chamber type and includes a reference chamber 10 and a sampling chamber 11 mounted on a printed circuit board 12 which is supported within a housing 13 on suitable studs or spacers 14. An intake air assembly 15 embodying the present invention is mounted on the housing 13 in axial alignment with the sampling chamber 11 and with the sampling chamber forms the ionization chamber for detecting changes in the density of combustion products in the ambient air. The reference chamber 10 is closed by a metal cap or corner plate 16 which acts as the ion collector during operation of the device. The chambers 10 and 11 are provided with buttons or discs containing radioactive material which provide the sources of alpha particles for ionization of air or other gas within the chambers. The radioactive discs are mounted on conducting posts which extend outside the chamber walls and are indicated at 17 and 18 for the chambers 10 and 11, respectively; the disc for the chamber 11 is indicated at 18a in FIG. 3. Flat circular conducting plates are provided in the chambers in face engagement with the bottom walls thereof and concentric with the cylindrical chambers, the plate for the chamber 11 being indicated at 18b in FIG. 3. These plates cover substantially the entire bottom walls and are in conducting relationship with the respective discs of the plates. An electric potential is applied across the chambers, the connections for applying these potentials being made to the post 17 and the cover plate 16 for the chamber 10 and the post 18 and the conducting screen 20 for the chamber 11. The electrical field produced by the potential difference between the screen 20 and the source is distributed over the cross sections of the chambers by the conducting plate 18b of the chamber 11 and the corresponding plate (not shown) in the chamber 10. The electric circuitry for applying the potentials to the chambers 10 and 11 and for detecting changes in the density of combustion products in the chamber in the ambient air are not essential to an understanding of the present invention and the circuit details have therefore not been illustrated in the drawing.

The combustion product detector illustrated in FIG. 1 senses changes in the combustion product density in the ambient air which reaches the interior of the chamber through the air inlet assembly 15. The ambient air is normally in circulation due to convection currents or to air moving devices in the area in which the detector is located. The air inlet assembly 15 is arranged to assure admission of ambient air to the sampling chamber regardless of the direction in which the air is moving. The details of construction of the air admitting assembly are shown in FIGS. 2, 3 and 4. The chamber 11 includes a block or body 21 of rigid synthetic plastic material such as clear tempered styrene. The block is provided with concentric annular rings or shoulders 22 and 23 which afford mounting of the cylinder on printed circuit boards or the like in any one of three different positions on either side of the board, the two end portions being of the same diameter are fitted in holes of that diameter in the printed board; the mid-portion determined by the diameter of the ring 22 requires a larger opening. The single cylinder 11 may thus be mounted in a relatively wide range of positions and its use in connection with printed circuit boards is thus flexible. Chamber 11 as illustrated in FIGS. 2 and 3 is enlarged by a relatively shallow right circular cupped recess 24 formed in the closure 15 and which is aligned

with the axis of the chamber 11 and forms a part of the chamber. A cupped metal screen 20 is mounted adjacent the inner walls of the recess. Ambient air as it moves over the closure plate 15 enters the inner cupped recess through radial slots 25 formed in the edge wall of the closure 15 and communicating with the interior thereof. It will thus be seen that air flowing directly across the closure 15 from one side to the other will enter slots on the one side, be directed generally toward the center of the cup and then leave through slots on the other side. Air moving directly toward the closure 15 axially thereof will enter through the slots 25 and also will enter through a central passage 26 of relatively small diameter. The rate at which air may enter through the slots 25 and the passage 26 is restricted by the screen 24 which limits the rate of flow of air into the ionization chamber. The screen extends beyond the opening of the cup a distance equal to the raised portions indicated at 27 and 28 to which the screen is secured on a collar 30 which has been illustrated as having a flange 31 to which the screen is welded, soldered or otherwise suitable secured. The flange 31 is provided with openings to afford passage of air therethrough, and these openings and the screen limit the rate of air flowing through the space between the housing 13 and the closure 15 provided by the raised portions 27 and 28. A flow of air through this space may for example be produced when air is moving directly against the plate 15 and the openings thus provide a relief of pressure within the chamber and prevent the building up of pressure. The passage 26 centrally of the closure plate 15 admits air to the interior of the ionization chamber when air is flowing across the plate 15 from one side to the other thereof. This admission of air through the passage 26 is effected by the velocity of the air passing the interior end of the passage 26 which produces a reduced pressure whereupon the air flows through the passage transversely of the flat bottomed wall of the cup and directs some air into the ionization chamber for circulation therein and thus assures a reliable sampling of the ambient air. It will be apparent that, regardless of the direction and movement of air over the closure plate 15, a portion of the air will be admitted to the interior of the ionization chamber where it is to be sampled. Movement of the air in the room thus will assure accurate sampling by providing a fresh supply of air as long as such movement continues. It will readily be apparent that the detector may be placed in any desired position on the sidewall, ceiling or other surface within an enclosure such as a room and will sample the condition of the air at such location, regardless of the direction of movement of the air within the room and also over a wide range of velocities of such movement, the screen restricting the rate of flow into the ionization chamber at the higher velocities.

For purposes of mounting the collector plate assembly or closure 15 in a unit such as illustrated in FIG. 1 holes 32 and 33 are provided which extend through the flange of the closure plate and lie within the edges of raised portions 27 and 28. Thus the studs 14 on which the assembly 15 is mounted provide an attaching arrangement which also secures the screen in place on the assembly. The screen 20 serves two functions, first as the ion collector plate of the ionization chamber and second, as an air flow restrictor.

The plastic bodies for the ionization chambers as indicated at 10 and 11 are identical in size although the

actual chambers are somewhat larger, the chamber 10 being enlarged by the spacing of the conducting corner plate 16 which extends beyond the edge of the plastic body, and the chamber 11 being extended by the closure plate assembly 15 as described above. By way of example, but not by way of limitation, it has been found that by constructing the chamber blocks 10 and 11 so that they have an interior right cylindrical chamber one inch in diameter, seven-eighths inch long and extending the chamber 10 about one-eighth inch to provide an enclosed chamber of 1 inch by 1 inch and the chamber 11 by about three-eighth inch highly satisfactory proportions of the ionization chambers are provided. The chamber 11 cooperates effectively with the inlet closure assembly 15 to assure accurate operation of the detector over a wide range of different ambient air conditions in the room or other closure in which the unit is installed.

While the invention has been disclosed in connection with a specific application thereof, various other modifications will occur to those skilled in the art. Therefore it is not desired that the invention be limited to the details illustrated and described and it is intended, by the appended claims, to cover all modifications which fall within the true spirit and scope of the invention.

I claim:

1. An ambient air admitting closure member for the ionization chamber of a combustion product detector comprising:
a rigid body having a flat portion and a rim therearound forming a cupped recess therein for providing one end portion of an ionization chamber, said body having a passage extending through said flat portion centrally thereof and providing communication between said recess and the ambient air and a plurality of slots spaced around said rim and entering the side of said recess, each of said slots being of a configuration for causing ambient air moving toward one side of said body in a path normal to the central axis of said chamber and entering said slots to flow over the surface of said flat portion and radially inward toward said central passage whereby the ambient air from the outside of said body will flow past the inner end of said passage and produce a flow of air through said passage into said recess transversely of the radial flow of air through said slots and whereby when ambient air flows axially against said chamber it will be admitted through said passage and flow from said cup recess toward said other end of the ionization chamber.
2. The invention as set forth in claim 1 wherein said flat and rim portions are circular and said slots extend radially into said recess.
3. The invention as set forth in claim 1 wherein said slots extend through the outer periphery of said flat portion and afford passage of air directly therethrough when flowing along paths normal to said flat portion.
4. The invention as set forth in claim 2 wherein said slots are equally spaced about said rim and tend to direct air across said passage regardless of the direction of flow of the ambient air.
5. The invention as set forth in claim 1 including means providing additional peripheral openings into the chamber adjacent said slots and shielded externally therefrom for affording a release of air from the chamber.

6. The invention as set forth in claim 1 including conducting means about said recess for providing an ion collector plate for the detector.

7. The invention as set forth in claim 1 having a cup shaped foraminous member within said cup adjacent 5 the walls thereof for limiting the rate of passage of air through said slots.

8. The invention as set forth in claim 7 wherein said foraminous member is a metal screen.

9. The invention as set forth in claim 8 including 10 means providing an insulated wall chamber opening toward said cup and having a radiation source therein, and means for producing an electric potential difference between said screen and said source for directing ions toward said screen whereby said screen constitutes 15 an ion collector plate.

10. The invention as set forth in claim 9 wherein said chamber is cylindrical, and including a circular conducting plate covering a major portion of the bottom wall of said chamber and in conducting relationship 20 with said source whereby the electrical field produced by said potential difference is distributed over the cross section of said chamber.

11. An ion chamber for combustion product detectors and the like comprising:

a body of electric insulating material having a right circular cylindrical chamber therein open at one end and having a flat bottom wall closing its other end, and

a flat circular plate in face engagement with said 30 other end concentric with said cylinder, and means providing a source of alpha particles at the center of said circular plate, wherein said circular plate covers the entire area of 35 said bottom wall.

12. An ion chamber for combustion product detectors and the like comprising:

a body of electric insulating material having a right

circular cylindrical chamber therein open at one end and having a flat bottom wall closing its other end, and

a flat circular plate in face engagement with said other end concentric with said cylinder, and means providing a source of alpha particles at the center of said circular plate, wherein the length of said cylindrical chamber is approximately the same as the diameter thereof and the length of the ion chamber is approximately 1 1/4 times the diameter of said cylindrical chamber.

13. An ion chamber assembly for apparatus utilizing a radioactive substance for detecting the presence of combustion products in the ambient air comprising:

- a. a body of insulating material having a chamber therein open at one end,
- b. a closure member for said open end, said member having a shallow right cylindrical recess providing a flat end wall,
- c. means for holding said body and said member in assembled relationship with said chamber and said recess in open communication and forming a substantially closed ion chamber,
- d. a radioactive source in said first mentioned chamber,
- e. the side wall of said closure member having a plurality of radially directed slots evenly spaced about the circumference thereof and opening into the interior thereof and affording a passage of air into said recess across the interior thereof and out the opposite side, and
- f. said flat wall having an opening centrally thereof for affording movement of air axially of said recess, the air stream moving through said recess between said slots from one side to the other inducing a flow of air through said opening and moving a portion of the air into the chamber in said body.
